UNITED STATES PATENT OFFICE.

WERNER LEHMAN, OF SOUTH MILWAUKEE, AND OTTO F. KAESER, OF MILWAUKEE, WISCONSIN, ASSIGNORS TO BUCYRUS COMPANY, OF SOUTH MILWAUKEE, WISCONSIN, A CORPORATION OF WISCONSIN.

RAILWAY TRACTION MECHANISM.

Application filed February 7, 1921. Serial No. 443,669.

To all whom it may concern:

Be it known that we, WERNER LEHMAN and OTTO F. KAESER, both citizens of the United States, and residents of South Milwaukee, in the county of Milwaukee and State of Wisconsin, and of Milwaukee, in the county of Milwaukee and State of Wisconsin, respectively, have invented certain new and useful Improvements in Railway Traction Mechanism; and we do hereby declare that the following is a full, clear, and exact description thereof.

Our invention relates to new and useful improvements in propulsion mountings for heavy excavating and similar machinery, and pertains especially to railway traction mechanism therefor.

In traction mechanism of this character, while it is advisable to permit at least one of the axles of the machine to tilt with respect to the main supporting frame during propulsion, it is practically necessary to hold the frame rigid with respect to the ground when the parts carried thereby are functioning. Therefore it is the primary object of this invention to provide a simply constructed bracing means, which, while normally not in use, may be quickly, swung to operative position when the excavating machinery or the like is to be brought into action.

It is furthermore an object of this invention to provide bracing means of this character which, while adapted to lie close against the main supporting frame when not in use, are rigidly mounted when in extended operative position.

Another object of the invention is to provide means which will serve both as a tie plate member and a jack-arm holding member.

With these general objects in view the invention resides in the novel features of construction, combination and arrangement of parts which will be hereinafter more particularly described and claimed, and shown in the accompanying drawings wherein—

Figure 1 represents a plan view, partly in section, of the main supporting frame of an excavator structure having our improvements applied thereto;

Figure 2 is a side elevational view of the parts shown in Figure 1;

Figure 3 is a transverse section taken on the plane of the line 3—3 of Figure 1;

Figure 4 is a transverse section taken substantially on the plane of line 4—4 of Figure 1, and

Figure 5 is a detail elevational view of the jack-arm sill.

Referring more particularly to the drawings, it will be seen that our invention is applied to the main supporting frame of an excavator or similar digging machine structure, said frame being substantially rectangular in shape and consisting of a pair of longitudinal spaced side bars or sills 1 and end bars or sills 2. The middle portion of this frame is braced by two pairs of intermediate transverse sills or bars 3 and 4; all of which bars as well as the side and end bars are preferably of heavy I-beam construction. A pair of side cover plates 5 are disposed on and extend inwardly from the top flanges of the side bars 1, and these plates are riveted to said side bars and the transverse bars, while a transverse cover plate 6 is disposed on each pair of the intermediate transverse bars 3 and 4 and riveted to their flanges.

A rack and track member preferably in the form of a single annular casting 7 is mounted on the several cover plates, it resting particularly on the cover plates 6 supported by the transverse bars 3 and 4, and overlapping the side cover plates 5 and the intermediate portions of the side bars 1 (see Figure 1). The casting 7 is riveted as at 8 to the several cover plates and is thus retained in proper relation to the different elements of the main frame. The rack and track member includes inwardly extending radial arms 9 which merge into a central bearing sleeve 10, and the portions of these arms adjacent their connection with the annular portion of the casting 7 are transversely widened to provide attaching plates 11 which overlie the transverse bars 3. The central bearing sleeve 10 receives a vertical propulsion shaft 12 which is connected with the machinery drive mechanism (not shown), and the upper end of said sleeve also forms a trunnion for the revolving frame (also not shown) which rests on the track portion of the casting 7.

The rack and track casting is further secured to the other parts of the frame by pairs of tie bolts 13 which are passed through said attaching plates 11, each pair

of said bolts straddling a respective transverse bar 3 and being connected at their lower ends by a suitable tie plate member to be later described. These bolts 13 obviously 5 take up the tilting stresses involved in the operation of the heavy machinery mounted on the main supporting frame and relieve such stresses from the various rivets, including the rivets 8. Increased rigidity of the 10 front end of the main supporting frame is obtained by mounting a combined bearing and bracing casting 14 between the front end bar 2 and the forward transverse bar 4 and securing the same midway of the ends of the 15 latter. Among other uses this casting 14 obviously aids in evenly distributing stresses imparted to the draw head 15.

A rear axle 16 is provided for the main supporting frame and is journaled in bearings 17 carried by the side bars 1. Railway track wheels 18 are mounted on the axle 16 inwardly of the bearings 17, and rotation thereof is obtained through a beveled pinion 19 on the axle 16 and a beveled gear 20 25 on a counter-shaft 21. The counter-shaft 21 extends longitudinally of the frame and has its forward end gear connected with the vertical propulsion shaft 12.

A tilting front axle 22 is also provided 30 for the main supporting frame, and this axle is pivoted intermediate its ends between the ears 23 of a head 24 which is formed on the lower end of a king-pin 25. As shown most clearly in Figure 4, this 35 king-pin 25 is mounted in the casting 14. The portion of the head 24 between the ears 23 is slightly convex as at 26 and is engaged by the upper edge of the axle 22 so that the latter may readily tilt.

40 The opposite ends of the axle 22 have spindle portions 27, the free ends of which are reduced as at 28 for wheel retaining collars 29. The railway track wheels 30 which are journaled on the spindle portions 27 are 45 disposed inwardly of the side bars 1 of the main supporting frame and have hubs of a less length than the length of said spindle portions so that it is possible to vary the relative distance between said wheels. In 50 other words a spacing collar 31 is disposed on each spindle portion 27 and is adapted to be selectively positioned between the inner end of the latter and the adjacent end of the wheel hub, or between the outer end 55 of the wheel hub and the adjacent retaining collar 29. Thus the wheels may be accommodated for different track gauges.

In this type of traction mechanism, since 60 it is desirable to hold the tiltable front axle 22 transversely of the main supporting frame at all times, depending stop brackets 32 are mounted under the lower flanges of the side bars 1 adjacent the ends of the axle 22. These brackets each include a flat bearing plate against which the adjacent retain-

ing collar 29 is adapted to slide, said retaining collars being squared as shown in Figure 2 and retained against rotation on the reduced ends 28 of the spindle portions 27 by pins 33.

70

For overcoming the tilting action rendered possible by this mounting of the front axle, a pair of bracing structures are provided, one being disposed to each side of the main supporting frame. Each of these 75 bracing structures includes a jack-arm 34 hung substantially midway its ends beneath a side bar 1 of the frame by a pivot shaft 35 carried thereby, this shaft being extended through a bracket 36 on said side 80 bar and through the lower flange of the latter. The outer end of the jack-arm 34 carries a jack-screw 37 having a head 38, whereas the opposite end is designed to be engaged with a jack-arm sill 39 when in 85 active operation.

The sills 39, one of which is provided for each jack-arm, are disposed longitudinally of the main supporting frame and substantially parallel with the side bars 1 thereof. 90 Their length is such that they bridge the space between the transverse bars 3 and are adapted to be held in engagement with the lower flanges thereof by said tie bolts 13. Thus the end portions of the sills 39 form 95 tie plate members for these bolts, their intermediate portions being of substantially I-beam construction. A stop rib 40 is formed between the horizontal flange portions of the sills 39 and is adapted to limit 100 the swinging movement of the jack-arms 34 in one direction (see Figure 1).

When inactive the jack-arms 34 lie as shown by the dotted lines in Figure 1, or in other words, substantially longitudinally 105 of the main supporting frame, they being held thus by retaining rods 41, one end of each of which is pivoted to the outer end of the jack-arms, whereas the other ends thereof are disposed in holes 42 in the lower flanges of the side bars 1. On the other hand when the jack-arms are in use and are disposed substantially at right angles to the main supporting frame, these rods 41 are hooked into other holes 43 in said flanges 110 of the side bars. Thus the jack-arms are retained against movement in one direction by these rods 41 and in an opposite direction by the stop ribs 40.

115 While we have shown and described a 120 preferred embodiment of our invention, it will be understood that various changes and modifications of structure may be employed to meet differing conditions of use and manufacture without departing in any manner from the spirit of the invention.

125 We claim:

1. In a traction mechanism, a supporting frame including side bars and transverse connecting bars, a superstructure track 130

5 mounted on said bars, pairs of tie-bolts extended through said track and embracing certain of said transverse bars, a jack arm sill secured to said frame by certain of said tie-bolts and constituting a tie-plate for said tie-bolts, and a jack-arm connected intermediate its ends to one of said side bars, one end of said jack-arm engageable with said sill, the other end projectable out-
10 wardly from said frame.

15 2. In a traction mechanism, a supporting frame including side bars, and transverse connecting bars a superstructure track mounted on said bars, pairs of tie-bolts ex-
20 tended through said track and embracing certain of said transverse bars, a jack-arm sill secured to said frame by certain of said tie-bolts and constituting a tie-plate for said said tie-bolts, and a jack-arm pivotally con-
25 nected intermediate its ends to one of said side bars so as to swing into and out of operative position, said sill being arranged to receive and brace one end of said arm when in operative position.

30 25 3. In a traction mechanism, a supporting frame including a pair of side bars, a pair of end bars connecting the side bars, a pair of spaced intermediately disposed transverse bars connecting said side bars, a super-
35 structure track mounted on the side and intermediate bars, a plurality of pairs of tie-bolts extending through the track, the bolts of each pair straddling one or the other of said intermediate bars of the frame, a pair of jack-arm sills disposed substan-
40 tially parallel with said side bars and se-
cured to the frame by adjacent pairs of tie-bolts, said sills forming tie-plates for the bolts and having arm end receiving por-
45 tions, and a jack-arm carried at its inter-
mediate portion by each side bar of the frame, the ground-engaging ends of the jack-arms extending outwardly of the frame, the opposite ends of the jack-arms

being engaged with said sills and disposed in said receiving portions. 45

4. A traction mechanism including a sup-
porting frame, a jack-arm having its inter-
mediate portion mounted on a substantially
vertical pivot at the side of the frame, and
50 a seat portion carried by the frame for
engagement and disengagement by the inner
end portion of the jack-arm when said arm
is swung transversely of the frame.

5. A traction mechanism including a sup-
porting frame having side bars, a jack-arm
having its intermediate portion mounted on
a substantially vertical pivot under one of
the side bars, and a seat portion carried
55 by the frame inwardly of the last mentioned
side bar for engagement with the inner
end portion of the jack-arm when said arm
is swung to extend transversely of the frame
whereby to afford cantilever support for
60 the outer or ground-engaging end of the
jack-arm.

6. A traction mechanism including a sup-
porting frame having side bars, a pivot
member carried by one of the side bars, a
jack arm mounted intermediate its ends on
70 said pivot member and adapted to extend
transversely of the side bars or substantially
longitudinally thereof, means for locking the
jack-arm in either of two positions, and
a seat portion carried by the frame inwardly
75 of the jack-arm carrying side bar for en-
gagement by the inner end portion of the
jack-arm when the same is swung trans-
versely of the frame whereby to form a cantil-
ever support for the outer end or ground-
80 engaging portion of the jack-arm.

In testimony that we claim the foregoing
we have hereunto set our hands at South
Milwaukee, in the county of Milwaukee and
State of Wisconsin.

WERNER LEHMAN.
OTTO F. KAESER.
